UNITED STATES PATENT OFFICE.

WILLIAM BERNSTEIN, OF NEW YORK, N. Y.

VEIL-FASTENER.

SPECIFICATION forming part of Letters Patent No. 701,133, dated May 27, 1902.

Application filed March 22, 1902. Serial No. 99,458. (No model.)

To all whom it may concern:

Be it known that I, WILLIAM BERNSTEIN, a citizen of the United States, and a resident of the city of New York, borough of Manhattan, 5 in the county and State of New York, have invented a new and Improved Veil-Fastener, of which the following is a full, clear, and exact description.

The object of the invention is to provide a 10 new and improved veil-fastener for permanent use on a lady's hat to allow of quickly and conveniently securing the veil in place, the fastener being rather inconspicuous, and hence does not mar the appearance of the 15 veil or hat.

The invention consists of novel features and parts and combinations of the same, as will be more fully described hereinafter and then pointed out in the claim.

20 A practical embodiment of the invention is represented in the accompanying drawings, forming a part of this specification, in which similar characters of reference indicate corresponding parts in all the views.

25 Figure 1 is a reduced perspective view of the improvement as applied to the front of a hat. Fig. 2 is an enlarged perspective view of the same applied to the rear of a hat, and Fig. 3 is an enlarged perspective view of the 30 improvement.

The improved veil-fastener consists, essentially, of an attaching-plate A, adapted to be sewed or otherwise fastened to the hat at any desired place thereon, preferably along the 35 rim, two or more fasteners being also preferably employed on the same hat, one at the front and the other at the rear, as indicated in Figs. 1 and 2. From the attaching-plate A extends a pin B, having the base portion

40 B' of its shank extending from the lower part of the plate in an outward and upward direction, the said base-plate terminating in an ogee-curved portion B², which extends inwardly and upwardly and terminates in a

point B³, ranging in the same direction and 45 reaching within a short distance of the front of the plate A, near the upper end thereof. Now when the attaching-plate is secured to the hat then the end of the veil or any portion thereof can be readily slipped onto the 50 point B³ and drawn downward over the curved portion B², and thus into the space formed between the attaching-plate and the lower or base end B' of the shank, the veil being prevented from slipping out of the pin by the 55 curved portion arranged at angles to the base portion of the shank and standing in the direction mentioned. Now by the arrangement described considerable space is formed between the pin and the attaching-plate to accommodate the veil, at the same time preventing the veil from becoming accidentally detached, torn, or creased, as is so frequently the case in tying the ends of the veil at the 60 back.

Having thus described my invention, I claim as new and desire to secure by Letters Patent—

A veil-fastener, comprising an attaching-plate, adapted to be secured to a hat, a pin 70 extending on the front face of the attaching-plate, and comprising a shank, having its base end extending at angles from the said plate and in an upward and outward direction, the base end of the shank terminating in an ogee-curved portion, extending inwardly and upwardly, and a point extending from the said 75 curved portion and in the same direction, and reaching within a short distance of the base of the attaching-plate, as set forth.

In testimony whereof I have signed my name to this specification in the presence of two subscribing witnesses.

WILLIAM BERNSTEIN.
